Atlys.

UNITED STATES PATENT OFFICE

CHRISTIAN A. BIRKEBAK, OF DETROIT, MICHIGAN, ASSIGNOR TO EX-CELL-O AIRCRAFT AND TOOL CORPORATION, OF DETROIT, MICHIGAN, A CORPORATION OF MICHIGAN

TOOL RETAINER

Application filed April 25, 1929. Serial No. 357,900.

The present invention relates to improvements in retainers for tools, such as punches, dies and the like, and is particularly applicable to heavy duty tools adapted for use in metal forming operations.

Tools of this character and the retaining means therefor in many instances are subjected to severe operating conditions. Thus, in punching metal of substantial thickness, a heavy force is applied to the punch to shear the metal, and a still greater force is required to withdraw the punch. The force required increases as the shearing clearance between the punch and the die is increased for greater thicknesses of metal, and is greater in hot shearing than in cold shearing.

The tools must be removable from the retaining means so as to permit replacement because of wear or changes in the character of the work to be performed. To this end, the retaining means must be provided with a suitable lock for holding the tools in position during operation, and for releasing the tools when desired.

It will be evident that the retaining means and particularly the lock should hold the tool firmly in place, without lost motion, during the operation, and should be of sufficient strength to withstand the severe forces imposed thereon. Heretofore, serious difficulties have been met with in this regard. In various prior retainers, the tools are not held securely in position, and the locks tend to crush or shear. Registration between the locks and the coacting parts on the tools is not accurate or positive, is difficult to effect when assembling the parts, and permits lateral play. In some instances, the locks also tend to injure the tools, and do not permit ease of replacement or substitution.

The primary objects of the present invention therefore reside in the provision of a new and improved tool retainer in which the tool may be readily inserted and removed when desired, which serves to hold the tool securely in position, and which is capable of withstanding the forces imposed thereon.

Further objects reside in the provision in a tool retainer of novel lock means which does not act directly against the shank of

the tool, and hence does not injure the latter in use, which serves to effect a positive registration, which will not crush readily, and which if mutilated somewhat still will maintain a positive registration and will not injure the punch or cease to be effective.

Another object is to provide lock means of the foregoing character the coacting parts of which on the retainer proper and the tool shank may be readily replaced when worn.

A general object resides in the provision of a tool retainer which is simple and relatively inexpensive in construction, and which can be made with simple and easy machine operations.

Further objects and advantages will become apparent as the description proceeds.

In the accompanying drawings, Fig. 1 is a plan view partially sectioned along line 1-1 of Fig. 3 of a punch retainer embodying the features of my invention.

Fig. 2 is a horizontal sectional view taken along line 2-2 of Fig. 3.

Fig. 3 is a vertical sectional view taken along line 3-3 of Fig. 1.

Fig. 4 is a vertical sectional view taken along line 4-4 of Fig. 1.

Fig. 5 is a transverse sectional view of a punch constituting a part of a modified form of my invention.

Fig. 6 is a fragmentary side view of the punch shown in Fig. 5.

Fig. 7 is a fragmentary sectional view taken along line 7-7 of Fig. 5.

Fig. 8 is a fragmentary sectional view of another modified form of the invention.

Fig. 9 is a fragmentary sectional view taken at right angles to the view in Fig. 8.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the draw-

ings, I have shown the invention embodied in a punch retainer, but it is to be understood that the invention is applicable to various types of tools.

5 Referring first to Figs. 1 to 4, the punch retainer comprises a socket member 10 which preferably is cylindrical in form, and which is formed with a central axial recess 11, preferably a bore, extending therethrough. The 10 bore 11 is adapted to receive the cylindrical shank 12 of a tool, such as the punch 13, with a close sliding fit. The socket member 10 is suitably mounted in a supporting member 14, and in the present instance is formed on its 15 inner end with a peripheral flange 15 seating in a notch 16 in the upper end of the member. A suitable backing plate 17 also is disposed in the notch 16 against the upper end of the socket member 10, and projects slightly above 20 the supporting member 14. The supporting member 14, with the socket member 10 and the plate 17 mounted therein, is removably secured, as by means of bolts 18, to a base 19 forming part of the operative element of 25 the machine (not shown). It will be evident that when the member 14 is removed from the base 19, the socket member 10 can be removed therefrom, and that when the member 14 is secured to the base 19, the socket member 30 and the plate 17 are clamped tightly in position. The base 19 and the plate 17 are formed respectively with registering openings 20 and 21 aligned with the shank 12.

Releasable means is provided for locking 35 the shank 12 securely against the backing plate 17. To this end, the socket member 10 is formed with a longitudinal keyway 22 along the bore 11. The keyway 22 opens to the ends of the member 10 and also to the bore 40 11. Secured to the shank 12 is a longitudinal key 23 having a snug sliding fit in the keyway 22. The key 23 may be secured to the shank 12 in different ways. In Figs. 1 to 45 4, a transverse notch 24 is milled in one side of the upper end of the shank 12 substantially to the center. In this instance, the key 23 is in the form of a plate backing against the root surface and snugly confined between the side surfaces of the notch 24, and is suitably secured in position by a rivet 25. The 50 key 23 extends substantially through the notch 24, and one end projects therefrom into the keyway 22. It will be evident that the key 23 is held securely against endwise movement or play, and that it can be removed and replaced when worn without scrapping of the tool. The projecting face 26 is substantially radial, and coacts with the adjacent face 55 27 of the keyway 22 to positively and accurately locate the tool peripherally without regard to whether or not the other face of the key is mutilated. Registration is easily and definitely effected.

A locking member, preferably in the form 60 of a ball 28, is arranged in wedging engage-

ment with the key 23. To this end, the ball is movably disposed in the inner end of an angular aperture or bore 29 formed in the socket member 10 and inclined to the rear face 30 of the key 23. One end of the bore 70 29 opens to the upper or inner end surface of the socket member 10, and the other end opens partly to the bore 11 and partly to the keyway 22. A coil spring 31 is disposed in the bore 29 between the backing plate 17 and the ball 28 in abutting engagement therewith, and serves to urge the ball 28 against the key 23. The outer end of the bore 29 75 also opens through an aperture 32 to the outer end surface of the socket member 10, this aperture permitting the insertion of a suitable tool (not shown) for raising the ball 28 out of engagement with the key 23 when it is desired to remove the punch. While the relative inclination between the key and the bore 29, represented by the character θ , is not closely fixed and may be varied within reasonable limits, preferably the angle θ is between 12 and 16 degrees.

Obviously, the notch 24 permits the ball 28 to project partly into the bore 11 for engagement with the key 23. To increase the possible range of engagement, the upper end of the shank 12 above the key 23 and next to the bore 29 is notched or cut away as indicated at 33. By reason of this construction, the wedging force is applied approximately at or within the circumference of the shank 12, and a relatively large ball 28 100 may be used.

The rear face 30 of the key 23 is formed with a straight longitudinal groove 34 conforming laterally substantially to the curvature of the ball 28 and constituting a raceway therefor. The groove 34 is inclined downwardly and inwardly into the key 23 at an angle slightly less than the angle θ so that its surface is still slightly inclined into the path of the ball 28. This inclination is represented by the angle ϕ which preferably is between 2 and 3 degrees.

In operation, the backing plate 17 takes the upward thrust. During the downward thrust, the ball 28 wedges tightly against the key 23 thereby holding the shank 12 securely against outward movement. The tools 115 13 can be removed easily and quickly by raising the ball 28 out of locking position.

It will be evident that the construction is 120 simple and inexpensive, and that the manufacturing operations therefor are easy. Simple milling operations will serve to form the notches 16 and 33 and the groove 34. The angular bore 29 need not be perfect, or located with great nicety relative to the shank 125 12 since it is not relied upon to locate the latter peripherally. At the same time the construction is compact, sturdy, efficient and not easily damaged. A large ball 28 may be provided without substantially increasing the 130

overall dimensions, and obviously is less liable to shear and crush. Accurate longitudinal and peripheral registration is provided. The shank 12 is located peripherally by a 5 fixed stop not exposed to injury, and is held securely against the stop by a force having a substantial moment arm. The wedge face 30 of the key 23 can be mutilated substantially without affecting the registration or 10 location of the parts. Since the ball 28 does not contact with the shank 12, it cannot injure or destroy the usefulness of the tool 13. When the key 23 is worn or mutilated, it can be replaced by a new key, thereby increasing 15 the life of the tool 13.

The form of the invention shown in Figs. 5, 6 and 7 differs from the first form only in the manner in which the key 23 is mounted on the shank 12, and hence corresponding parts 20 of the two forms are identified by like reference characters. In this form, the upper end of the shank 12 is formed with a longitudinal groove 35 in which the key 23 is snugly disposed. Projecting laterally into a bore 25 36 in the upper end of the shank 12 and across the top of the key 23 is a pin 37 for holding the key in position. The projecting end of the pin 37 is milled down to less than the thickness of the key 23, and the upper end 30 of the latter is curved to conform to the pin. The sides of the groove 35 are milled partially away, as indicated at 38 and 39, to provide clearance and in one instance to expose more of the key 23 to the ball 28. Preferably, 35 the key 28 and pin 37 are welded to each other, and also to the shank 12 as indicated at 40.

The form of the invention illustrated in Figs. 8 and 9 is generally similar to the first forms, and corresponding parts thereof are 40 therefore identified by the like reference characters. In this form, the key 23 is secured in a longitudinal groove 41 in the shank 12. The bore 29 does not open to the central bore 11, but only to the keyway 22. Hence, the envelope locking action occurs outside of the bore 11.

I claim as my invention:

1. A tool retainer comprising, in combination, a socket member having an aperture 50 adapted to receive a tool and having an elongated key-way opening to said aperture along one side thereof, a tool having a sliding fit in said aperture, an elongated longitudinal key rigid on said tool and having a sliding fit in said key-way, and spring-pressed wedge means projecting into said key-way and co-acting with said key to prevent withdrawal of said tool from said aperture.

2. A tool retainer comprising, in combination, a socket member having an aperture 55 adapted to receive a tool and having a key-way opening to said aperture along one side thereof, a tool having a sliding fit in said aperture, a key rigidly secured to said tool 60 and having a sliding fit in said key-way, said

key being formed with a wedge surface, and a spring-pressed ball projecting into said key-way and engaging said surface to exert a wedging action thereon whereby the tool is held against withdrawal from said aperture. 70

3. A tool retainer comprising, in combination, a socket member having an elongated aperture, having a key-way opening to said aperture longitudinally thereof, and having a second aperture inclined to said key-way and opening thereto, a tool slidably disposed in said first mentioned aperture, abutment means disposed at one end of said first mentioned aperture to substantially define the 75 innermost position of said tool, a key rigidly secured to said tool and projecting laterally therefrom into said key-way, and a spring-pressed ball in said last mentioned aperture projecting partially into said key-way into 80 wedging engagement with said key to prevent withdrawal of said tool from said first mentioned aperture.

4. A tool retainer comprising, in combination, a socket member having a central bore, 90 having a spline key-way opening to said bore longitudinally thereof and having an inclined recess opening to said key-way, a tool disposed in said bore, a key extending longitudinally on said tool and projecting slidably into said key-way, said key being formed 95 with a wedge surface inclined into said recess, and a spring pressed ball in said recess engaging said surface.

5. A tool retainer comprising, in combination, a socket member having a central aperture, a spline key-way opening to one side of said aperture and longitudinally thereof, and an aperture inclined downwardly towards said keyway and opening thereto, a 100 tool disposed in said central aperture, a flat key rigidly secured to and projecting from said tool into said key-way, said key being formed with a wedge surface inclined downwardly into the line of said inclined aperture, a ball disposed in said inclined aperture in wedging engagement with said surface, and spring means acting on said ball to urge the latter downwardly, whereby said key is clamped against one side of said key-way to effect peripheral location of said tool, and whereby said tool is held against withdrawal from said central aperture. 105

6. A tool retainer comprising, in combination, a socket member having a cylindrical tool receiving bore, a cylindrical tool portion disposed in said bore with a sliding fit, a clamping plate secured to said tool portion and defining a clamping surface extending 110 generally longitudinally of said bore, said member being formed with a clamping surface opposed to and slightly inclined longitudinally of said bore relatively to said first mentioned surface, and spring pressed means 115 120

interposed between said surfaces and having a wedging engagement with said plate.

7. A tool retainer comprising, in combination, a socket member having a tool receiving bore and a recess opening to said bore, a tool disposed in said bore with a sliding fit, a clamping member secured to one side of said tool and projecting into said recess, and having a wedge surface inclined to the axis of said bore, said recess defining a wedge surface inclined to the axis of said bore in the same general direction as but at a greater angle than said first mentioned surface, and yielding means removably interposed in wedging engagement between said surfaces.

8. A tool retainer comprising, in combination, a support having an aperture and formed with an elongated stop shoulder longitudinally of said aperture, a tool in said aperture, an elongated longitudinal shoulder on said tool extending across said stop shoulder, and means for clamping said last mentioned shoulder against said stop shoulder to effect peripheral location of said tool in said aperture.

9. A tool retainer comprising, in combination, a socket member having a bore and a key-way opening to said bore longitudinally thereof, and an aperture inclined downwardly toward said key and opening at its lower end to said key-way and said bore, a tool disposed in said bore, a clamping member secured to said tool and projecting laterally therefrom into said key-way, said clamping member being formed with a downwardly inclined groove substantially arcuate in cross section and projecting at an angle into the line of said aperture, a spring-pressed ball in said aperture, said ball projecting partially into said key-way and said bore into clamping engagement with the wall of said groove.

10. A tool retainer comprising, in combination, a support having a bore and formed with an elongated stop shoulder longitudinally of said bore, a tool in said bore, an elongated longitudinal shoulder on said tool extending across said stop shoulder, and spring-pressed wedge means for clamping said last mentioned shoulder against said stop shoulder to effect peripheral location of said tool in said bore.

11. A tool retainer comprising, in combination, a socket member having an aperture and a key-way opening to said aperture along one side thereof, a tool having a sliding fit in said aperture, and formed with a recess, a clamping member secured in said recess, said member being formed with a wedge surface, and a spring-pressed ball projecting into said recess and engaging said surface to exert a wedging action thereon whereby the tool is held against withdrawal from said aperture.

12. A tool retainer comprising, in combination, a support having an aperture therein, a tool in said aperture, a wedge member

set in said tool and having a wedge surface, said support having an aperture inclined longitudinally of said first mentioned aperture and opening to said surface, and a spring pressed clamping member in said last mentioned aperture engaging said surface.

13. A tool retainer comprising, in combination, a supporting member, a socket member removably supported in said supporting member, a backing plate positioned across the top of said socket member, said socket member having a central axial bore opening at its upper end to said backing plate, and having a square key-way opening longitudinally to one side of said bore, one side of said key-way being radially disposed relative to said bore, said socket member having a second bore opening at the top to said backing plate and at the bottom to said key-way and said bore, a tool shank disposed in said first mentioned bore in substantial end abutting engagement with said backing plate, said shank being formed with a lateral notch substantially to the center thereof, a key plate secured in said notch and projecting slidably into said key-way, the projecting end of said key being formed with a straight downwardly and inwardly inclined groove substantially arcuate in lateral cross section, said groove being inclined downwardly at a small angle into the line of said inclined bore, a ball disposed in the lower end of said inclined bore and projecting partially into said key-way and said central bore into wedging engagement with the wall of said groove, and spring means in said bore for urging said ball downwardly.

14. A tool retainer comprising, in combination, a socket member having a central axial bore, and having a square key-way opening longitudinally to one side of said bore, one side of said key-way being radially disposed relative to said bore, and having a second bore inclined downwardly to said key-way, a tool shank disposed in said bore, a key plate secured in said shank and projecting slidably into said key-way, the projecting end of said key being formed with a straight downwardly and inwardly inclined groove substantially arcuate in lateral cross section, said groove being inclined downwardly at a small angle into the line of said inclined bore, a ball disposed in the lower end of said inclined bore and projecting partially into said key-way and said central bore into wedging engagement with the wall of said groove, and spring means in said bore for urging said ball downwardly.

In testimony whereof, I have hereunto affixed my signature.

CHRISTIAN A. BIRKEBAK.
